CLAIM

The ornamental design for a three axis, three button mouse, as shown and described.

DESCRIPTION

FIG. 1 is a perspective view of the mouse;
FIG. 2 is a top view of the mouse;
FIG. 3 is a left side view of the mouse;
FIG. 4 is a right side view of the mouse;
FIG. 5 is a bottom view of the mouse;
FIG. 6 is a front view of the mouse; and,
FIG. 7 is a back view of the mouse.

The broken line drawings of top and side buttons and the cord in all views are for illustrative purposes only and form no part of the claimed design.
